UNITED STATES PATENT OFFICE

2,604,106

MEANS FOR CONTROLLING DRAINAGE OF
LIQUID FROM WASHING MACHINES

Sven Börje Fredrik Carlstedt, Stockholm, Sweden

Application August 24, 1948, Serial No. 45,807
In Sweden April 11, 1945

11 Claims. (Cl. 134—186)

1

The invention relates to dish-washing machines, other washing machines, and the like apparatus, having means to circulate a liquid supplied to the machine past a drain for the discharge of the liquid after finishing the work.

The main object of the invention is to provide means in machines of the type set forth which enable the drain to be constructed without any closing valves or other mechanical valve-devices.

Further objects of the invention will be apparent from the following description of a preferred embodiment thereof considered in connection with the accompanying drawing, which forms part of this specification, and in which:

Fig. 1 is an end-elevation, partly in vertical cross-section, of a dish-washing machine according to the invention;

Fig. 2 is a corresponding longitudinal section of the machine; and

Fig. 3 is a vertical cross-section on an enlarged scale of the lower part of the machine.

The dish-washing machine illustrated in the drawing has an upper portion 1 providing a washing space and a lower tank portion 2 in the form of a substantially horizontal trough provided with a concave bottom wall. The portion 1 which preferably has a square bottom and rectangular side walls made of thin sheet-plate, is covered by a lid 3 and contains a basket 4 for dishes to be cleaned, for example plates 5. The lower portion 2 the walls of which preferably also are made of sheet-plate and which is of an oblong shape and located under the wash space 1, is quite open towards the latter space. In the trough 2 a rotatable horizontal bladed impeller element 7 has its shaft extending somewhat beyond said tank at one side thereof to carry a pulley 6, whereby said shaft may be driven by means of a belt (not shown) from any appropriate source of power and motion. The trough 2 is further provided with an inlet conduit 8 for washing liquid, controlled by an inlet valve 9.

Drainage means for the apparatus is provided by a sump 16, which, as will be seen from Fig. 2, is substantially shorter than the trough 2 and the major portion of which is located to one side of the vertical center line of the trough. Sump 16 has a substantially horizontal and flat bottom wall 14 located below the level of the concave bottom wall of the trough between suitable end walls, and a curved side wall extending upwardly from the bottom wall of the sump to merge smoothly with one of the side walls of the trough.

The portion 13 of the bottom wall of the trough opposite the sump 16 terminates in a lip spaced above a wall portion 12 extending laterally from

2

the bottom wall 14 of the sump to provide a vertical port 15 located below the envelope of the impeller and opening axially of the trough laterally into the sump 16.

The wall portions 12 and 13 overlap to provide a laterally extending portion of a drain passage 10 which is in open communication with port 15.

As seen from Fig. 3, drainage from the trough is by gravity flow to the sump 16 and through the port 15 and drain passage 10 to waste; in the direction of arrow A, the flow along the bottom of the sump and through the port being substantially parallel with a tangent to the envelope of the impeller.

The impeller is rotated to circulate the liquid in the trough in the direction denoted by arrow B so that it is discharged upwardly along one side of the concave wall of the trough into the washing space to perform its washing function and returns from the washing space by gravity to the opposite side of the trough.

Circulation of the liquid in such direction also causes a part of it to be discharged over the lip at the edge of wall 13 into sump 16 across and away from the port 15, so that flow due to such circulation opposes the gravity flow through port 15 to the drain passage 10 and liquid is retained in the trough in spite of the presence of a fully open drain port and drain passage.

As will be evident from Fig. 2, the blading of the impeller 7 overlies the full axial extent of the sump 16 and as will be seen from Fig. 3 the substantially flat horizontal bottom wall 14 of the sump results in impingement of liquid thrown off the blades of the impeller against the wall 14 at an angle substantially greater than 90°. These factors result in more effective opposition by the circulatory flow to the gravity drainage flow than would be the case if the bottom of the sump were curved, as along the dotted line C, or if the impeller blading did not sweep over the full axial extent of the drain port.

From the foregoing it is believed the operation of the apparatus will be largely obvious. To place the machine in operation, the impeller is started first and the desired amount of liquid admitted to the trough 2 through the inlet 8, liquid being retained due to the circulatory action set up by the impeller. When the washing or rinsing operation has been completed the impeller is stopped and upon the resulting cessation of the circulatory flow, the unopposed gravity flow through the open drain port and passage empties the machine.

While one more or less specific embodiment of

the invention has been shown, it is to be understood that the same is for purpose of illustration only, and that the invention is not limited thereby, but its scope is to be determined by the appended claims.

What I claim is:

1. A machine of the character described having a receptacle providing an upper washing space and a communicating lower trough for liquid, the wall of said trough being formed to provide an open sump located below and extending laterally toward one side of said trough, an impeller rotatably mounted axially in said trough, the axis of said impeller being substantially horizontal, a drain passage located below said trough and terminating in a drain port opening laterally and axially into one side of said sump below said impeller, the adjacent portion of said passage extending laterally from said port toward the other side of said trough, the bottom wall of said sump in front of said port being substantially flat and horizontal, and means for turning said impeller in a predetermined direction to discharge liquid across and away from said port and upwardly thereafter into said washing space, the portion of said passage adjacent to said port extending in a direction substantially opposite that of the flow of said discharged liquid whereby the flow of the discharged liquid opposes flow of liquid from the receptacle through said port and said passage.

2. A machine as set forth in claim 1 in which the bottom wall of said sump curves upwardly from the substantially flat portion to merge with the side wall of the trough.

3. In a machine of the character described having a receptacle for receiving articles to be washed, a substantially horizontal trough disposed below said receptacle, said trough having spaced side and end walls and a concavely curved bottom wall, said trough being in open communication with said receptacle, a bladed impeller disposed in said trough and mounted for rotation about a substantially horizontal axis, the lower portion of the envelope of said impeller being adjacent the inner surface of said bottom wall, means for rotating said impeller in a predetermined direction to circulate liquid in said trough upwardly along one side wall and into said receptacle to wash said articles and downwardly from said receptacle along the opposite side wall, drainage means for said trough and said receptacle comprising a generally rectangular sump in the bottom of said trough, said sump having spaced end walls, a bottom wall and a curved side wall, said curved side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain passage outside of but tangential to the envelope of said impeller and opening toward said curved side wall whereby upon rotation of said impeller in said predetermined direction liquid will flow over said lip and into said sump away from said drain passage to oppose the counter flow of liquid from said trough into said sump and drain passage and when said impeller is at rest liquid may freely flow into said sump and said drain passage.

4. In a machine of the character described having a receptacle for receiving articles to be washed, a substantially horizontal trough disposed below said receptacle, said trough having spaced side and end walls and a concavely curved bottom wall, said trough being in open communication with said receptacle, a bladed impeller disposed in said trough and mounted for rotation about a substantially horizontal axis,

10 the lower portion of the envelope of said impeller being adjacent the inner surface of said bottom wall, means for rotating said impeller in a predetermined direction to circulate liquid in said trough upwardly along one side wall and into said receptacle to wash said articles and downwardly from said receptacle along the opposite side wall, drainage means for said trough and said receptacle comprising a sump in the bottom of said trough, said sump having a bottom wall and a curved side wall, said curved side wall merging into said bottom wall and the first mentioned side wall of said trough, the major portion of said sump being disposed at one side of the vertical center line of said trough in the direction of flow of liquid caused by rotation of said impeller, the bottom wall of said trough terminating in a lip above the bottom wall of said sump in overlapping relation thereto and short of the first mentioned side wall to provide a drain passage tangential to the envelope of said impeller and opening toward said curved side wall whereby upon rotation of said impeller in said predetermined direction liquid will flow over said lip and into said sump away from said drain passage to oppose the counter flow of liquid from said trough into said sump and drain passage and when said impeller is at rest liquid may freely flow into said sump and said drain passage.

30 5. In a machine of the character described having a receptacle for receiving articles to be washed, a substantially horizontal trough disposed below said receptacle, said trough having spaced side and end walls and a concavely curved bottom wall, said trough being in open communication with said receptacle, a bladed impeller disposed in said trough and mounted for rotation about a substantially horizontal axis, the lower portion of the envelope of said impeller being adjacent the inner surface of said bottom wall,

40 means for rotating said impeller in a predetermined direction to circulate liquid in said trough upwardly along one side wall and into said receptacle to wash said articles and downwardly from said receptacle along the opposite side wall, drainage means for said trough and said receptacle comprising a sump in the bottom of said trough, said sump having a bottom wall and a curved side wall, said curved side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain port outside of the envelope of said impeller opening toward said curved side wall whereby upon rotation of said impeller in said predetermined direction liquid will flow over said lip and into said sump and said drain port and when said impeller is at rest liquid may freely flow into said sump and said drain port.

50 6. In a machine of the character described having a receptacle for receiving articles to be washed, a substantially horizontal trough disposed below said receptacle, said trough having spaced side and end walls and a concavely curved bottom wall, said trough being in open communication with said receptacle, a bladed impeller disposed in said trough and mounted for rotation about a substantially horizontal axis, the lower portion of the envelope of said impeller being adjacent the inner surface of said bottom wall,

45 means for rotating said impeller in a predetermined direction to circulate liquid in said trough upwardly along one side wall and into said receptacle to wash said articles and downwardly from said receptacle along the opposite side wall, drainage means for said trough and said receptacle comprising a sump in the bottom of said trough, said sump having a bottom wall and a curved side wall, said curved side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain port outside of the envelope of said impeller opening toward said curved side wall whereby upon rotation of said impeller in said predetermined direction liquid will flow over said lip and into said sump and said drain port and when said impeller is at rest liquid may freely flow into said sump and said drain port.

55 7. In a machine of the character described having a receptacle for receiving articles to be washed, a substantially horizontal trough disposed below said receptacle, said trough having spaced side and end walls and a concavely curved bottom wall, said trough being in open communication with said receptacle, a bladed impeller disposed in said trough and mounted for rotation about a substantially horizontal axis, the lower portion of the envelope of said impeller being adjacent the inner surface of said bottom wall,

60 means for rotating said impeller in a predetermined direction to circulate liquid in said trough upwardly along one side wall and into said receptacle to wash said articles and downwardly from said receptacle along the opposite side wall, drainage means for said trough and said receptacle comprising a sump in the bottom of said trough, said sump having a bottom wall and a curved side wall, said curved side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain port outside of the envelope of said impeller opening toward said curved side wall whereby upon rotation of said impeller in said predetermined direction liquid will flow over said lip and into said sump and said drain port and when said impeller is at rest liquid may freely flow into said sump and said drain port.

65 8. In a machine of the character described having a receptacle for receiving articles to be washed, a substantially horizontal trough disposed below said receptacle, said trough having spaced side and end walls and a concavely curved bottom wall, said trough being in open communication with said receptacle, a bladed impeller disposed in said trough and mounted for rotation about a substantially horizontal axis, the lower portion of the envelope of said impeller being adjacent the inner surface of said bottom wall,

70 means for rotating said impeller in a predetermined direction to circulate liquid in said trough upwardly along one side wall and into said receptacle to wash said articles and downwardly from said receptacle along the opposite side wall, drainage means for said trough and said receptacle comprising a sump in the bottom of said trough, said sump having a bottom wall and a curved side wall, said curved side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain port outside of the envelope of said impeller opening toward said curved side wall whereby upon rotation of said impeller in said predetermined direction liquid will flow over said lip and into said sump and said drain port and when said impeller is at rest liquid may freely flow into said sump and said drain port.

6. In a machine of the character described, a substantially horizontal trough for receiving liquid, said trough having spaced side and end walls and a concavely curved bottom wall, a bladed impeller disposed in said trough and mounted for rotation about a substantially horizontal axis, the lower portion of the envelope of said impeller being adjacent the inner surface of said bottom wall, means for rotating said impeller in a predetermined direction to circulate liquid in said trough upwardly along one side wall and downwardly along the opposite side wall, drainage means for said trough comprising a generally-rectangular sump in the bottom of said trough, said sump having spaced end walls, a bottom wall and a curved side wall, said curved side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain passage outside of but tangential to the envelope of said impeller and opening toward said curved side wall whereby upon rotation of said impeller in said predetermined direction liquid will flow over said lip and into said sump away from said drain passage to oppose the counter flow of liquid from said trough into said sump and drain passage and when said impeller is at rest liquid may freely flow into said sump and said drain passage.

7. In a machine of the character described, a substantially horizontal trough for receiving liquid, said trough having spaced side and end walls and a concavely curved bottom wall, a bladed impeller disposed in said trough and mounted for rotation about a substantially horizontal axis, the lower portion of the envelope of said impeller being adjacent the inner surface of said bottom wall, means for rotating said impeller in a predetermined direction to circulate liquid in said trough upwardly along one side wall and downwardly along the opposite side wall, drainage means for said trough comprising a sump in the bottom of said trough, said sump having a bottom wall and a side wall, said side wall merging into said bottom wall and the first mentioned side wall of said trough, the major portion of said sump being disposed at one side of the vertical center line of said trough in the direction of flow of liquid caused by the rotation of said impeller, the bottom wall of said trough terminating in a lip above the bottom wall of said sump in overlapping relation thereto and short of the first mentioned side wall to provide a drain passage outside of but tangential to the envelope of said impeller and opening toward said curved side wall whereby upon rotation of said impeller in said predetermined direction liquid will flow over said lip and into said sump away from said drain passage to oppose the counter flow of liquid from said trough into said sump and drain passage and when said impeller is at rest liquid may freely flow into said sump and said drain passage.

8. In a machine of the character described, a substantially horizontal trough for receiving liquid, said trough having spaced side and end walls and a concavely curved bottom wall, a bladed impeller disposed in said trough and mounted for rotation about a substantially horizontal axis, the lower portion of the envelope of

said impeller being adjacent the inner surface of said bottom wall, means for rotating said impeller in a predetermined direction to circulate liquid in said trough upwardly along one side wall and downwardly along the opposite side wall, drainage means for said trough comprising a sump in the bottom of said trough, said sump having a bottom wall and a side wall, said side wall merging into said bottom wall and the first mentioned side wall of said trough, the bottom wall of said trough terminating in a lip above the bottom wall of said sump in overlapping relation thereto and short of the first mentioned side wall to provide a drain port outside of the envelope of said impeller opening toward the side wall of said sump whereby upon rotation of said impeller in said predetermined direction liquid will flow over said lip and into said sump away from said drain port to oppose the counter flow of liquid from said trough into said sump and drain port and when said impeller is at rest liquid may freely flow into said sump and said drain port.

9. In a machine of the character described a substantially horizontal trough for receiving liquid, said trough having a concavely curved bottom wall, a bladed impeller disposed in said trough and mounted for rotation about a substantially horizontal axis, the lower portion of the envelope of said impeller being adjacent the inner surface of said bottom wall, means for rotating said impeller in a predetermined direction to circulate liquid in said trough upwardly along one side of said bottom wall and downwardly along the opposite side, drainage means for said trough comprising a sump in the bottom of said wall, said sump having a bottom wall and end walls, the bottom wall of said trough terminating in a lip above the bottom wall of said sump short of the first mentioned side of the bottom wall of said trough to provide a substantially vertical drain port below the envelope of said impeller, said impeller being so disposed axially relative to the bottom and end walls of said sump that upon rotation of said impeller in said predetermined direction liquid will be discharged over said lip and into said sump away from said drain port to oppose the gravity flow of liquid from said trough into said sump and through said drain port.

10. In a machine of the character described a substantially horizontal trough for receiving liquid, said trough having a concavely curved bottom wall, a bladed impeller disposed in said trough and mounted for rotation about a substantially horizontal axis, the lower portion of the envelope of said impeller being adjacent the inner surface of said bottom wall, means for rotating said impeller in a predetermined direction to circulate liquid in said trough upwardly along one side of said bottom wall and downwardly along the opposite side, drainage means for said trough comprising a sump in the bottom of said wall, said sump having a bottom wall and end walls, the bottom wall of said trough terminating in a lip above the bottom wall of said sump short of the first mentioned side of the bottom wall of said trough to provide a substantially vertical drain port below the envelope of said impeller, said impeller having at least one blade disposed over said sump and extending over at least the whole axial extent of said sump whereby upon rotation of said impeller in said predetermined direction liquid will be discharged over said lip and into said sump away from said drain port to oppose the gravity flow of liquid from said trough into said sump and through said drain port.

11. A machine of the character described having a receptacle providing an upper washing space and a communicating lower horizontal trough for liquid, said trough having a concavely curved bottom wall, a bladed impeller disposed in said trough and extending axially over the major portion of said trough, said impeller being mounted for rotation about a substantially horizontal axis, the lower portion of the envelope of said impeller being adjacent said bottom wall, drainage means for said trough comprising a sump located below said trough and terminating in a substantially vertical drain port opening laterally into said bottom wall below the lower portion of said envelope, the axial extension of said sump being substantially less than that of said impeller and means for rotating said impeller in a predetermined direction to discharge liquid

across and away from said port and upwardly thereafter into said washing space whereby the flow of the discharged liquid opposes the gravity flow of liquid through said port.
